UNITED STATES PATENT OFFICE.

CHRISTIAN WILLIAM MEINECKE, OF JERSEY CITY, NEW JERSEY.

DESIGN FOR A WATER-BAG.

SPECIFICATION forming part of Design No. 34,116, dated February 19, 1901.

Application filed October 18, 1900. Serial No. 33,519. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Water-Bag, of which the following is a specification.

My invention relates to a new and original design for water-bags, and is illustrated in the accompanying drawing, in which the figure is a perspective view of the bag.

The leading features of my design reside in a water-bag having convex or outwardly curved shoulders, concaved or inwardly curved sides, convex lower corners, and concave or inwardly-curved bottom. The contour of the water-bag, beginning with the shoulders, describes a continuous series of successive ogee curves.

In the said drawing the reference-letter A indicates the water-bag, the shoulders E E of which are convex or outwardly curved, and

C C the sides, which are concave or inwardly curved.

D D are the corners of the bag, which are convex or outwardly curved and which merge or extend into an inwardly-curved bottom B.

The entire contour of the bag, beginning with the shoulders E E, describes a continuous series of ogee curves, as shown.

My invention presents a water-bag having a novel, pleasing, and distinguished appearance.

Having thus described my invention, what I claim is—

The design for a water-bag substantially as herein shown and described.

In testimony whereof I have hereunto set my hand in the presence of two subscribing witnesses.

CHRISTIAN WILLIAM MEINECKE.
